UNITED STATES PATENT OFFICE.

LEWIS T. HOUGHTON, OF WORCESTER, MASSACHUSETTS.

QUILLER-WIRE HOLDER.

Application filed June 12, 1922. Serial No. 567,822.

To all whom it may concern:

Be it known that I, LEWIS T. HOUGHTON, a citizen of the United States, residing at Worcester, in the county of Worcester and State of Massachusetts, have invented a new and useful Quiller-Wire Holder, of which the following is a specification.

This invention relates to the wires forming eyes and used for guiding yarn in winding it upon bobbins or cops for use in weaving.

The principal objects of the invention are to provide a wire which will not be weakened by screw threading or otherwise cutting into its shank and yet capable of supporting the eyes firmly on the rod on which they are located; also to provide a construction in which the wires can be taken out if broken and replaced very readily without throwing away the holder or bracket for supporting them, and to provide means which will support all the wires at a distance from the supporting rod, thus giving the wires a firmer position and permitting of their being adjusted by bending as desired without weakening the hold which the holding device has upon them. The invention also involves other features, as will appear.

Reference is to be had to the accompanying drawing, in which—

Fig. 1 is a plan of a series of quiller wires constructed in accordance with this invention;

Fig. 2 is a front view of the same, and Fig. 3 is an end view.

In machines for quilling it is customary to provide yarn guides in the form of so-called quiller wires which are screwed into a malleable iron bracket or holder. A line of these brackets are secured to a rod running along the machine, each held in place by means of an integral screw. The wires themselves, on account of the rapid action of the yarn in running through the eyes, has to be hardened or they will have to be replaced very often indeed. Being hardened and being screw threaded on the end which enters the bracket they are very brittle and frequently break off at the screw thread. It is not worth while to unscrew the stump which is left in the thread so the bracket and its remaining wire are taken off and a new bracket substituted ordinarily. The breakage is a very important and annoying feature in this class of work and ma-

terially retards production as well as being responsible for considerable expense.

This invention is designed to avoid this breakage and at the same time to provide a quiller wire which, instead of being supported only at its extreme end where it is the weakest, is clamped to the rod at that end. It is also supported quite a distance from the end so that it will have a firm support and so that it can be bent a little to adjust its position without running any risk of breaking it because it has no weak spot produced by threading its circumference. The invention also involves the provision of a bracket that is cheaper to manufacture because it is made of sheet metal and provides a single fastening device for holding the quiller wire, or preferably a pair of quiller wires, in the bracket and holding the bracket on the rod. It also saves the drilling and threading of the malleable bracket and threading of the guide wire.

For these purposes I have shown a machine having the ordinary rod 10 extending across it and provided with a series of brackets 11 each for supporting two hardened quiller wires 12 although each bracket, if desired, can support one or a larger number. This bracket preferably is formed of a flat piece of sheet metal doubled over to provide a space at the fold for receiving the rod 10. It is arranged so that it has two binding flanges 13 perforated to receive a binding bolt 14 and the upper one carries the nut therefor on its upper surface. By tightening this nut the rod 10 is clamped between the two flanges 13 and the bracket is firmly held on the rod, and at the same time it firmly clamps the wires.

Furthermore, the quiller wires 12 project straight back under rod, one on each side of the bolt, and are clamped between the rod and lower flange by tightening the nut. Thus the bolt and nut serve two purposes. In addition to this the lower flange 13 is bent up at its outer edge 15 and provided with a notch 16 for each wire. This elevates the wire off the floor of the flange 13, affords a rest for the wire at a distance from the rod and prevents sidewise displacement.

The wires preferably are flattened where they pass under the rod to ensure them against rotation on their own axes. They can be bent as desired beyond the notches 16 without loosening them so that the attendant will not have to be very careful about their

exact location when clamping them and the bracket to the rod. Any ordinary variation can be corrected after they are fixed by the bolt.

- 5 In use the brackets and quiller wires are set in position and clamped by turning the nuts at the top. Then the wires are bent a little up or down or sideways, if necessary, to bring them to the proper position. There is no danger of breaking or injuring them in clamping them up tight or of loosening them if they have to be adjusted several times. They can be hardened as much as necessary without really increasing the danger of breakage. The expense is reduced because only one screw is used in fastening the bracket and two wires. By supporting them at two points they are firmly located and yet readily adjustable.
- 20 Although I have illustrated and described only one form of the invention, I am aware of the fact that other modifications can be made therein by any person skilled in the art without departing from the scope of the invention as expressed in the claims.

25 Therefore, I do not wish to be limited to all the details of construction herein shown and described, but what I claim is:—

1. In a quiller wire support, the combination with a U-shaped bracket for receiving a supporting rod between its flanges, of a pair of quiller wires having ends, one end of each extending along one flange toward the rear thereof, a rod lying over said ends and

means spaced from the rod and between the rod and the eye-ends of said wires for forcing the rod against the wires to clamp them together.

2. The combination with a supporting rod and a quiller wire having an eye, of a support therefor comprising a piece of sheet metal bent double to receive the supporting rod in the bend thereof and having two flanges projecting beyond the rod toward the eye of the wire, along one of which the wire extends into contact with the under side of the rod, one of said flanges engaging the wire at a distance from the end thereof, and means for forcing the two flanges toward each other to bind the wire to the rod and the rod between the flanges.

3. The combination with a supporting rod and a quiller wire having an eye, of a support therefor comprising a piece of sheet metal bent double to receive the supporting rod in the bend thereof and having two horizontal parallel flanges projecting beyond the rod, between one of which and the rod the extreme end of the wire is clamped, one of said flanges being bent at its end toward the other and having a notch for engaging the wire at a distance from the end thereof, and means for forcing the two flanges toward each other to bind the wire to the rod and the rod between the flanges.

65 In testimony whereof I have hereunto affixed my signature.

LEWIS T. HOUGHTON.
